TILE PARTITION

Filed Dec. 13, 1930

Fig. 1.

UNITED STATES PATENT OFFICE

JAMES H. RYAN, OF ST. LOUIS, MISSOURI

TITLE PARTITION

Application filed December 13, 1930. Serial No. 502,057.

This invention relates to tile partitions; and an object is to provide an improved tile partition comprising a series of tiers of tiles and metallic channel members supporting the tiles in proper relationship to form a partition wall, in combination with means providing passages through the wall composed of the tiles and channel members for receiving and enclosing electric circuit wires and the like.

Another object of the invention is to provide an improved tile partition comprising a series of tiers of tiles having passages therethrough for receiving and enclosing electric circuit wires of all descriptions, metal tubing, conduits and all other wire protective devices used in electric work, in combination with upright channel members engaging the tiers of tiles and holding them in proper alinement, and means forming passages between the ends of the tiles and the channel members for conducting the wires upwardly or downwardly through the partition wall, and means for supporting plaster on the surfaces of the partitions constructed as aforesaid.

Another object of the invention is to provide an improved tile for use in constructing partitions and walls having one or more tubular passages therethrough opening into a box intermediate of the sides and ends of the tile to permit electric wires to be passed through said passages and outwardly through said boxes to connection with switches or other attachments as may be desired.

Another object of the invention is to provide an improved wall forming tile embodying the improved combination of elements and features of construction herein disclosed, reference being made to the accompanying drawings, in which—

Fig. 1 is a horizontal sectional view of a wall section taken approximately on the line 1—1 of Fig. 2 illustrating features of the present invention.

Fig. 2 is a side elevation of a portion of a partition embodying the present invention.

Fig. 3 is a perspective view of one of the tile blocks.

Fig. 4 is a perspective view of one of the

channel supporting members before the ties are bent to extend oppositely from the flanges.

Fig. 5 is a perspective view of a portion of one of the supporting members showing the ties bent to extend oppositely from the flanges.

Fig. 6 is a perspective view of a portion of a channel member used at the beginning of a partition wall.

Fig. 7 is a perspective view showing portions of supporting members used against a wall in the final construction of a partition.

The body of the partition wall comprises a number of blocks or tiles 1 arranged in vertical tiers, with occasional location at selected positions of selected tiers of specially constructed tiles 2. Thus, each tier is composed of a series of blocks or tiles 1 seated edgewise one upon the other with occasional interposition of a tile 2 of the same dimensions as the tiles 1. The completed partition wall may be surfaced with a layer 3 of plaster or other surfacing material applied to and engaging with the surfaces of the tiles and with the supports with which the tiles are engaged so as to provide a complete partition wall of finished and ornamental appearance. The tiles may be constructed with longitudinal ribs 4 separated by spaces 5 so as to obtain better supporting engagement with the plaster or other surfacing material. At one end of the partition wall a channel member support is located and is arranged and combined with the ends of the adjacent tier of tiles, so that the ends of all of the tiles in the adjacent tier are engaged in the channel of said member.

This channel member comprises a portion 6 having at each side a flange 7 which project approximately at right angles from the portion 6 and are spaced apart a sufficient distance to receive and embrace the ends of the tiles 1 and 2 between them. This channel member may be mounted against a wall or at one side of a door or other opening or elsewhere at the beginning of the partition wall.

Each intermediate support for the tiles comprises a metallic member including a main or body portion 8 and two flanges 9 projecting from the edge of the body portion 8 in the same direction and spaced apart a sufficient

distance to receive between them the ends of the tiles 1 and 2 forming a tier of tiles. This intermediate channel member is a duplicate of the end channel member above described, 5 with the exception that the flanges 9 are cut to provide ears or ties 10 that may be bent to extend oppositely from the flanges 9. Thus, each flange 9 is constructed with a series of pairs of diverging slits intersecting 10 at a distance from the outer edges of the flanges 9 and diverging to intersection with the main body portion 8 of the support. These slits provide ears or ties 10 that may be slightly deflected when initially cut, as 15 shown in Fig. 4 of the drawings, and bent finally when applied to use approximately to the position shown in Fig. 5. These ties are of sufficient length to engage the ends of adjacent tiles, as will be clearly understood by 20 references to Figs. 1 and 2 of the drawings, while the ends of an adjacent tier of tiles are engaged between the flanges 9 of the supporting member.

Each of the tiles 1 has in each end thereof 25 a vertical groove or channel 11 formed between projecting ribs 12. The flanges 7 of the end support and the flanges 9 of the intermediate support are of greater width than the depth of the grooves 11, so that the said 30 flanges will engage the sides of the tiles for the full length of the flanges 12 and extend beyond the bottoms of the grooves 11 so as to engage the main body portions of the tiles. Also, the ties 10 are of greater length than 35 the length of the flanges 11, so that said ties extend beyond the bottoms of the grooves 11 and engage the body portions of the tiles.

It is now clear that the grooves 11 form 40 passages at the ends of each tier of tiles and between the tiles and the channel member supports. These passages are continuous, so that electric circuit wires and the like may be confined therein during the building of the partition wall, thus eliminating any subsequent 45 necessity of defacing the walls for enclosing electric wires therein. Moreover, the wires may easily be placed in the walls after the walls are completed without defacing any substantial surfaces of the walls.

Each of the tiles 2 has embedded therein a 50 number of longitudinal metallic tubes 13, the ends of which open into the channels 11. These tubes 13 permit electric circuit wires to be placed therein during the construction 55 of the wall or after the wall has been constructed without defacing or marring the surface of the walls. The portions 8 of the intermediate channel members have holes 14 therethrough which are spaced so as to be in 60 alinement with or approximately in alinement with the tubes 13 in order to permit the electric circuit wires to be passed through a long stretch of wall, even after the walls have been erected and without defacing or marring the surfaces of the walls.

The tiles 2 embed a metallic box 15 which opens toward either side of the tiles and which has holes 16 registering with tubes 17 constituting passages from the box 15 to the grooves 18 at the ends of said tiles 2 corresponding to the grooves 11 in the tiles 1. Thus, the wires may be bent laterally to connection with switches or other connections, as desired. The tiles 2 also embed other longitudinal tubes 19 corresponding in all respects to the tubes 13. These tubes 17 and 19 are arranged and spaced in accordance with the arrangement and spacing of the tubes 13 and the holes 14, so that the electric circuit wires may readily be passed therethrough. 70 75 80

A support for finishing the end of a partition against another wall, for instance, may be of the type shown in Figs. 1 and 7, the same comprising a pair of metallic angle members, either or both of which may be 85 placed in position finally after the tiles are arranged and assembled in tiers to the height of the partition or to any other desired height. One of said angle members comprises flanges 90 20 and 21 extending at right angles to each other and constructed and arranged so that the flange 20 may be extended across the end of the tier of tiles and the flange 21 may be located at the side of the tier of tiles. The cooperating angle member is of similar construction and comprises a flange 22 and a flange 23 extending at right angles to said flange 22. This cooperating angle member is designed to be embodied in the partition structure by extending the flange member 22 95 100 between the end of the tier of tiles and the wall adjacent to which the tier of tiles terminates and arranging the flange 23 at the side of the tier of tiles opposite the flange 21 of the cooperating angle member. This leaves the grooves 11 forming a passage between the end of the tier of tiles and the flanges 20 and 22.

The manner of erecting a wall of my improved tiles and supports is now clear. The 110 plaster or plastic surfacing material is applied to the tiles and engages into all spaces and interstices so as to obtain firm engagement with the wall surfaces. The wires may be extended longitudinally or vertically 115 through the walls at nearly any desired position and, when the walls are constructed, the tiles 2 may be placed therein at points where there is no likelihood or possibility of need for the boxes 15. 120

A wall of this construction dispenses with the necessity and desirability of using mortar and the like, thus producing a fireproof construction which can be erected much faster than brick or tile partitions using mortar. The wall possesses the advantages of providing facilities for the insertion of the electric wires at any time, either before or after the completion of the walls without marring or defacing the plastered surfaces. 125 130

5 The metallic studs and tubes prevent this wall from crumbling when subjected to excessive heat, because these metallic elements act as reinforcements for the tiles and cannot be destroyed by fire. Even though one or more tiles should be removed from the wall, the remaining tiles remain rigid and will not crumble from heat.

10 The invention may be varied within the considerable scope of equivalent limits permissible without departure from the nature and principle thereof. I do not restrict myself unessentially, but what I claim and desire to secure by Letters Patent is:

15 1. A partition comprising adjacent tiers of tiles having the tiles of each tier laid one upon the other, supports for holding adjacent tiers of tiles in proper alinement and for holding the tiles of the respective tiers of 20 tiles superimposed and having openings therethrough opposite the ends of the tiles of the respective tiers, and means forming vertical passages between the ends of the tiers of tiles and said supports and in communication 25 with said openings.

2. A partition comprising adjacent tiers of tiles having the tiles of each tier laid one upon the other, supports for holding adjacent tiers of tiles in proper alinement and for holding 20 the tiles of the respective tiers of tiles superimposed and having openings therethrough opposite the ends of the tiles of the respective tiers, means forming vertical passages between the ends of the tiers of tiles and said 25 supports and in communication with said openings, and tubes embedded in the respective tiles opening into said passages.

3. A partition comprising adjacent tiers of tiles, a support for said tiers of tiles engaging and holding the tiles in alinement and having openings therethrough opposite the ends of the tiles, and means forming passages through said tiles in communication with said openings and with each other.

4. A partition comprising adjacent tiers of tiles, a support for said tiers of tiles engaging and holding the tiles in alinement and having openings therethrough opposite the ends of the tiles, means forming passages through said tiles in communication with said openings and with each other, and lateral openings in certain of said tiles in communication with said passages.

5. A wall comprising adjacent tiers of tiles having the tiles of each tier laid one upon the other, one of said tiers of tiles having a vertical groove in the end thereof that is toward an adjacent tier of tiles, and a channel member mounted between said tiers of tiles and having its side portions engaging the sides of the tiles and extending beyond the bottom of said groove.

6. A wall comprising adjacent tiers of tiles having the tiles of each tier laid one upon the other, one of said tiers of tiles having a ver-

tical groove in the end thereof that is toward an adjacent tier of tiles, a channel member mounted between said tiers of tiles and having its side portions engaging the sides of the tiles and extending beyond the bottom of 70 said groove, and tubes embedded in said tiles and having one end opening into said groove and the opposite end opening at the opposite end of the tiles.

7. A partition comprising adjacent tiers of tiles, a support for said tiers of tiles engaging and holding the tiles in alinement and having openings opposite the ends of the tiles, means forming passages through said tiles in communication with said openings, 80 and means forming communication between said passages at the ends of the tiles.

8. A partition comprising adjacent tiers of tiles, a support for said tiers of tiles engaging and holding the tiles in alinement and having openings opposite the ends of the tiles, means forming passages through said tiles in communication with said openings, means forming communication between said passages at the ends of the tiles, and boxes embedded in 90 certain of said tiles and opening toward one side thereof and being in communication with certain of said passages.
